(57) **CLAIM**

The ornamental design for a construction ball cover, as shown and described.

DESCRIPTION

FIG. 1 is a top front right isometric view of the construction ball cover.

FIG. 2 is bottom left back isometric view of the construction ball cover.

FIG. 3 is a front side elevation view of the construction ball cover, the back side elevation view being a mirror image.

FIG. 4 is a left side elevation view of the construction ball cover, the right side elevation view being a mirror image.

FIG. 5 is a top elevation view of the construction ball cover; and,

FIG. 6 is a bottom elevation view of the construction ball cover.

The broken lines shown in the drawings form no part of the claimed design. The hollow interior of the construction ball cover forms no part of the claimed design.
